UNITED STATES PATENT OFFICE.

MARVIN A. GYSEL, OF ROCHESTER, NEW YORK.

SIGNAL.

1,273,606.

Specification of Letters Patent.

Patented July 23, 1918.

Continuation of application Serial No. 171,943, filed May 31, 1917. This application filed January 5, 1918. Serial No. 210,529.

To all whom it may concern:

Be it known that I, MARVIN A. GYSEL, a citizen of the United States, and resident of Rochester, in the county of Monroe and State of New York, have invented certain new and useful Improvements in Signals, of which the following is a specification.

The present invention relates to signals, and while illustrated and described in connection with direction signals for use on vehicles it is capable of embodiment in signals of various types. An object of this invention is to provide an operating mechanism for signals so constructed as to effect the alternate movement of a signal member toward and from signaling position on successive movements of an operating member from a normal position. Another object of the invention is to combine with such an operating mechanism a locking means which will hold the signal member in either of its two positions until the operating member is actuated.

To these and other ends, the invention consists of certain parts and combinations of parts all of which will be hereinafter described, the novel features being pointed out in the appended claims.

In the drawings:—

Figure 1 is an interior view of the casing of the signal showing the signaling member retracted;

Fig. 2 is a view of the open side of the casing through which the signaling member is projected;

Figs. 3 and 4 are detail views showing two positions of the operating means, the first showing the position of the parts when the signaling member is retracted and the second showing the position of the parts when the signaling member is projected and the operating member is shifted slightly to retract the signaling member;

Fig. 5 is a detail view showing the signal attached to one side of a wind shield of an automobile, the signaling member being retracted; and

Fig. 6 is a view showing the signal on the opposite side of the vehicle with the signaling member projected.

In the illustrated embodiment of the invention, 1 indicates the motor vehicle to the

opposite sides of which the casings 2 of two signals are secured. Each casing in this instance is formed of two sections and 55 encloses a signaling member of any desired form. Preferably this member is in the form of a lazy tongs 3 with two short inner links 3^a pivoted on a common axis 3^b. Between its ends the lazy tongs carries guides 60 pieces 4 secured pivotally at 4^a to one of the central pivots of the lazy tongs and operating on guides 5 formed on the inner faces of the casings 2.

For projecting and retracting the signaling member through the open side of the casing, an operating mechanism is provided which in this instance comprises an operating member 6 preferably mounted to swing or oscillate on the pivot 3^b of the lazy tongs 70 and having a cord 7 or other similar means secured to its swinging end. A spring 8 or other device may act on the operating member to return the latter to normal position. Connection between the operating 75 member and the signaling member is so constructed that the former on successive movements away from its normal position alternately projects and retracts the signaling member from the casing. This connection in this instance embodies a latch 9 pivoted at 10 to the operator 6 and having a projection 11 near the swinging end for engagement alternately with two abutments 12 and 13 on a pivoted member 14 pivoted at 14^a. The abutments 12 and 13 are so arranged that one lies on one side of the normal position of the latch while the other lies on the other side of the normal position of the latch, the said normal position being 90 such that the direction of pull on the latch in normal position intersects the axis of the pivoted member 14. The latch is preferably held in its normal position by a spring device which, in this instance, comprises two 95 spring arms 15 coiled about a common pin 16 and anchored in the casing at 17. One spring arm returns the latch to normal position when the latch is released after having shifted the signaling member in one direction and the other spring arm returns the latch after the latch has shifted the signaling arm in the other direction. In order to direct the latch abutments 12 and 13 the

member 14 has two converging faces 12^a and 13^a forming a tapered projection between them in line with the pivot of the member 14.

To the end of locking the signaling member both in projected and in retracted positions, locking means may be provided comprising preferably interlocking portions on the latch 9 and the pivoted member 14. In this instance the latch 9 is provided with a lateral projection 18 while the pivoted member 14 is provided with a projection 19 in line with the pivot of said member, said projection 19 having notches 19^a and 19^b on opposite sides thereof in which the projection 18 is alternately adapted to be received, after the pivoted member 14 has been shifted by the latch. This interlocking connection is established by the spring 8 which returns the operating member 6 to its normal position, as shown in Fig. 3, while at the same time causing the projection 18 to enter the notch 19^a or 19^b, depending on which direction the member 14 has been shifted.

Assuming the parts are in the positions shown in Fig. 1, and it is desired to project the signaling member 3: the cord 7 is pulled, thus shifting the operating member 6 toward the left and compressing the spring 8. This causes the projection 11 on the latch 9 to enter into engagement with either the face 12^a or the face 13^a, depending on the position of the pivoted member 14. The face 12^a or 13^a directs the projection toward one of the abutments 12 or 13 which when engaged transmits the motion of the oscillatory operating member 6 to the pivoted member 14, due to the fact that the pull will be applied to the pivoted member on one side of the pivot 14^a, and the pivoted member through the link 20 which is connected to the signaling member 3 by the pivot 4^a, transmits the motion to the signaling member. Before the projection 11 shifts the pivoted member 14, the projection 18 is disconnected from the pivoted member 14, due to the fact that a slight lost motion takes place between the latch 9 and the pivoted member 14, while the projection 11 is traveling over either the surface 12^a or 13^a.

From the foregoing it will be seen that there has been provided a signal into which the signaling element may be alternately projected or retracted through successive movements of an operating member in one and the same direction away from a normal position, the operating member being returned to the normal position under the action of the spring or other suitable device, without effecting any movement of the signaling member. The mechanism for producing this result is simple in construction and not liable to get out of order. Furthermore, it has provision whereby the signaling member is locked both in projected and in retracted position, this locking means be-

ing released by such operating mechanism before the signaling member is shifted.

This application is a continuation of an application filed by me on May 31, 1917, Serial No. 171,943.

What I claim as my invention and desire to secure by Letters Patent is:—

1. A signal comprising a member movable in opposite directions, a signal member connected to said member to move to signaling position when the first named member is moved in one direction and away from signaling position when the first named member is moved in the other direction, an operating member, a spring for holding the operating member in a normal position, and connection between the operating member and the first named member having provision for moving the first named member alternately in opposite directions on successive movements of the operating member away from normal position.

2. A signal comprising a signaling member movable toward and from signaling position, an operating member having a normal position, and connection between the operating member and the signaling member having provision for moving the signaling member alternately to and from signaling position on successive movements of the operating member from normal position.

3. A signal comprising a signaling member in the form of lazy tongs, a pivoted member having a link connection with the lazy tongs, an operating member having a normal position, and means for engaging said pivoted member alternately on opposite sides of its pivot to project and retract the lazy tongs on successive movements of the operating member from normal position.

4. A signal comprising a signaling member, a pivoted member connected to the signaling member, an operating member having a normal position, and means for engaging said pivoted member alternately on opposite sides of its pivot to project and retract the signaling member on successive movements of the operating member from normal position.

5. A signal comprising a signaling member, a pivoted member connected to the signaling member, an oscillatory operating member having a normal position, and a latch pivoted to the operating member to engage the pivoted member alternately on opposite sides of its pivot to project and retract the signaling member on successive movements of the operating member from normal position.

6. A signal comprising a signaling member, a pivoted member connected to the signaling member, an oscillatory operating member having a normal position, a latch pivoted to the oscillatory operating member to engage the pivoted member alter-

nately on opposite sides of its pivot on successive movements of the operating member from normal position, and spring means acting on the latch to cause such alternate engagement.

7. A signal comprising a signaling member, a pivoted member connected to the signaling member, an oscillatory operating member, a latch pivoted to the operating member to engage the pivoted member alternately on opposite sides of the pivot to project and retract the signaling member, and interlocking devices on the latch and the pivoted member for holding the pivoted member against movement in both positions.

8. A signal comprising a signaling member movable to and from signaling position, an operating member having a normal position, a connection between the operating member and the signaling member having provision for moving the signaling member alternately to and from signaling position on successive movements of the operating member from normal position, said connections also having provision for locking said signal in its two positions.

9. A signal comprising a pivoted member movable in opposite directions, a signaling member connected to said member to move the signaling member to signaling position when the first named member is moved in one direction and away from signaling position when said first named member is moved in the other direction, an operating member, a spring for holding the operating member in normal position, and a latch operated by said operating member to engage the first mentioned member on opposite sides of its pivot, said latch and pivoted member having interlocking portions which hold said pivoted member in its two shifted positions.

10. A signal comprising a pivoted member, a signaling member operated by said pivoted member to move to signaling position when the pivoted member is moved in one direction and away from signaling position when the pivoted member is moved in the other direction, an operating member,

and a latch having a projection thereon, the pivoted member having two abutments on opposite sides of its pivot to be engaged by said projection on the latch, said pivoted member also having two converging faces for directing the projection to said abutments alternately.

11. A signal comprising a pivoted member, a signaling member operated by said pivoted member to move to signaling position when the pivoted member is moved in one direction and away from signaling position when the pivoted member is moved in the other direction, an operating member, a latch having a projection thereon, the pivoted member having two abutments on opposite sides of its pivot to be engaged by said projection on the latch, and said pivoted member also having two converging faces for directing the projection to said abutments alternately, interlocking portions on the latch and the said pivoted member for holding the pivoted member against movement in its two shifted positions, the interlocking portions being disconnected when the latch is moved in contact with one of the inclined faces toward one of the abutments, and a spring tending to hold the operating member in a normal position and to effect the interlocking between the latch and the pivoted member.

12. A signal comprising a pivoted member, a signaling member connected to said pivoted member to move to signaling position when the pivoted member is moved in one direction, and away from signaling position when the pivoted member is moved in the other direction, an operating member, a latch connected to the operating member and adapted to engage the pivoted member alternately on opposite sides of its pivot, interlocking devices between the latch and the pivoted member broken by the movement of the operating member, and a spring acting on the operating member to move it to a normal position and to effect the interlocking connection between the latch and the pivoted member.

MARVIN A. GYSEL.
